DESIGN FOR A STREET TENNIS BAT

William G. Fletcher, Bogota, N. J.

Application April 21, 1938, Serial No. 76,676

Term of patent 7 years

To all whom it may concern:

Be it known that I, William G. Fletcher, a citizen of the United States, residing at Bogota, in the county of Bergen and State of New Jersey, have invented a new, original, and ornamental Design for a Street Tennis Bat, of which the following is a specification, reference being had to the accompanying drawing, forming part thereof.

In the drawing, Fig. 1 is a side elevational view of the street tennis bat showing my design; Fig.

2 is an edge elevational view and Fig. 3 is a top plan view.

The characteristic features of the design reside in the specific configuration of the street tennis bat ornamented as shown.

I claim:

The ornamental design for a street tennis bat, substantially as shown and described.

WILLIAM G. FLETCHER.
